UNITED STATES PATENT OFFICE.

GILBERT E. WHITE, OF DES MOINES, IOWA.

FLUID-PRESSURE FEEDING MECHANISM.

1,374,789.

Specification of Letters Patent. Patented Apr. 12, 1921.

Original application filed April 15, 1918, Serial No. 228,593. Divided and this application filed January 20, 1919. Serial No. 272,200.

To all whom it may concern:

Be it known that I, GILBERT E. WHITE, a citizen of the United States of America, and resident of Des Moines, Polk county, Iowa, have invented a new and useful Fluid-Pressure Feeding Mechanism, of which the following is a specification.

The subject matter of this invention was formerly included in and has been divided 10 out of my application filed April 15, 1918, Serial Number 228,593, for air-blast plastering machine.

The object of this invention is to provide an improved construction for fluid-pressure 15 feeding mechanism for advancing a rotatable disk or feeding member formed with a plurality of pockets adapted to receive plastic material from a receptacle, to position such pockets successively for action of an 20 air-blast to discharge the plastic material.

A further object of this invention is to provide means connected with and operable in conjunction with the means for successively directing blasts of fluid pressure to 25 effect the forcible discharge of measured quantities of plastic material, for successively bringing such measured quantities of plastic material within the range of such successive blasts.

30 My invention consists in the construction, arrangement and combination of elements hereinafter set forth, pointed out in my claims and illustrated by the accompanying drawing, in which—

35 Figure 1 is an elevation, partly in section, of the complete air-blast discharging apparatus and the fluid-pressure feeding mechanism involving my present invention. Fig. 2 is a sectional elevation of a portion of the apparatus at right angles to Fig. 1. Fig. 3 is a cross-section on an enlarged scale on the line 3—3 of Fig. 2, portions being broken away to economize space. Fig. 4 is a bottom plan of a portion of the machine.

45 In the construction of the apparatus as shown the numeral 10 designates a suitable receptacle or tank, generally cylindrical in form and vertically disposed. A niche or pocket 11 is formed in the wall of the receptacle 10 and extends from a point adjacent the upper end of said receptacle to a point near the lower end thereof, where said niche is formed with a bottom 12 which is

provided with an opening 13. A feeding member 14, preferably formed as a metal 55 disk, is mounted on the bottom 15 of the receptacle 10 and pivoted at its center thereto, preferably by means of a stud 16 having a conical upper end portion or head 17 within the receptacle and secured by a key 18 beneath said bottom. The feeding member 14 extends and is adapted for rotary travel between the bottom 12 of the niche and the bottom 15 of the receptacle. The receptacle or tank 10 is adapted to receive and contain 60 the plastic material to be discharged, and the means for directing intermittently the air blasts for such purpose is fully illustrated and described in my parent application above referred to, and is here illustrated and described only for the purpose of 65 providing a setting and basis for the clear and full understanding of the present invention.

A tubular standard 19 is mounted in the 75 niche 11 and is formed with a base adapted to be secured to the bottom 12 of said niche, the bore of said standard preferably tapering upwardly and communicating at its lower end with the hole 13 in said bottom 80 12. The standard 19 extends approximately one-half the height of the niche 11 and at its upper end is formed with a globular valve casing 20 having a valve seat 21 at its lower end adapted to receive a ball valve 85 22 and close the passage through said standard at times. A hollow, laterally extending boss 23 is formed on the standard 19 immediately below the valve casing 20 and said boss is closed at its outer end by a 90 cap 24. A rock shaft 25 is journaled horizontally in and extends across and projects at both ends from the boss 23 and an elbow 26 is mounted on and secured by a set screw 27 to said rock shaft within said boss and standard. The free end of the elbow 26 engages the lowermost point of the ball valve 22, thus adapting said elbow to raise said valve at times. A blast chamber 28 is provided and is formed with a tubular arm 29 100 tapped into the upper end of the standard 19 above the valve casing 20, and said blast chamber also is provided with a vertically disposed cylinder 30 approximately parallel with and spaced from the arm 29. A pet 105 cock or relief valve 31 is tapped into the

upper portion of the blast chamber 28 and has the function of relieving, when opened manually, any air-lock which may occur in the operation of the apparatus. A globular 5 valve casing 32 is formed at the initial end of the blast chamber 28 and a ball valve 33 loosely mounted in said casing co-operates with a seat 34 to close entrance to the blast chamber at times. A cut-off valve casing 10 35 is threaded on the upper end of the valve casing 32 and carries a cut-off valve 36, shown conventionally, adapted for manual actuation to control entrance to the valve casing 32. A supply pipe 37 is tapped into the cut-off valve casing 35 and serves to supply the operating medium such as compressed air from a tank or pump (not shown) to the blast chamber. The lower end portion of the cylinder 30 normally is 15 closed by a cap 38 mounted thereon and locked against accidental removal by a set screw 39. A piston rod 40 is mounted for reciprocation in the cylinder 30 and blast chamber 28, having slide bearings in the center of the cap 38 and in a brace 41 formed in the blast chamber. The upper end portion of the piston rod 40 is adapted loosely to engage at times with and raise the ball valve 33 from the seat 34. A piston 20 head 42 is fixed to and between the ends of the rod 40 and is adapted to reciprocate within the cylinder 30. A washer 43 is mounted loosely on the piston rod 40 and rests on the cap 38. An expansive coil 25 spring 44 is mounted within the cylinder 30 and impinges at opposite ends on the piston head 42 and washer 43, said spring having the function of returning the piston head to its uppermost position in the cylinder. An 30 arm 45 is fixed to one outer end portion of the rock shaft 25 and normally is inclined upwardly and outwardly. A pitman 46 is pivoted at its forked upper end to the outer end portion of the arm 45 and extends loosely 35 through a hole in the outermost portion of the bottom 12 of the niche 11, whereby stability is given to said pitman in reciprocatory operation hereinafter described. The pitman 46 is formed with a longitudinal slot 47 and is externally threaded throughout the length of 40 said slot and compassing the lower terminal of the pitman. A lever 48 is mounted loosely through the slot 47 of the pitman 46 and is pivoted at one end to a forked 45 lower end portion of the piston rod 40, the opposite end portion of said lever extending loosely through a hub 49 (Fig. 3), which hub is pivoted, as by a concealed bolt 50, to a boss 51 formed or mounted on one 50 side of the standard 19 just above the base of said standard. Spaced nuts 52, 53 are screwed on the pitman 46 on opposite sides of the lever 48 and are secured by jam nuts 54. The spacing of the nuts 52, 53 provides 55 for a range of movement of the lever 48 be-
tween alternate engagements of said lever with said nuts during further travel of the lever which ultimately effects a reciprocatory movement of the shaft 25, oscillation of the elbow 26 and unseating or seating of the ball valve 22. The feeding disk 14 operates between the bottom 12 of the niche 11 and the bottom 15 of the receptacle and consequently operates between the bore of the standard, the hole 13 and an elbow 55 70 formed on or fixed to the bottom 15 and communicating with a discharge pipe or hose 56. Pockets 57, preferably holes of greater diameter at their lower than at their upper ends and arranged in an annular row 75 concentric with the axis of the stud 16, are formed in the marginal portion of the disk 14 and are adapted to register successively with the hole 13 and the initial end of the elbow 55. It is the function of the pockets 57 to 80 carry plastic material from the receptacle 10 and hold it, in partition-like manner, across the passage from said hole to said elbow; and when such condition exists and the valve 22 is opened, a blast of air passes through the 85 standard 19 and discharges said plastic material from said pocket 57 in register as described, through the elbow 55 and discharge pipe 56. To effect such result it is necessary to provide means for intermittently rotating the disk 14 successively to 90 present pockets 57 in register with the hole 13 and elbow 55 and such means should be synchronized with the mechanism above described for controlling the valves 22 and 33. 95
The operating means for the disk 14 consists preferably of a bell-crank lever 58 suitably fulcrumed on a bracket 59 and provided at the upper end of its vertical arm with a spring-pressed dog 60 adapted to engage and co-operate successively with ratchet teeth 61 formed in the lower side of said disk; said dog being arranged to operate through a slot 62 in the bottom 15 of the receptacle. The bell-crank lever 58 is operated and the movement thereof synchronized with the valve-operating means by a connecting rod 63 forked at both ends and pivoted at said ends respectively to the lever 48 and the outer end of the recumbent arm 105 of said bell-crank lever. 110
In practical use of the apparatus as described the plaster or cementitious material, or any other suitable material desired to be used with the device, is mixed directly 115 in or received after mixing by the receptacle 10 and owing to the weight thereof said material is supported directly on the disk 14 and fills the exposed pockets 57 of said disk. After loading the receptacle 10 with 120 the desired quantity of material the valve 36 is opened manually; it being presumed that the supply pipe 37 is in communication with a source of compressed operating medium such as air in sufficient quantity and 125 130

at required pressure for actuation of the device and carrying out the various functions dependent thereon as above described; and the parts of the apparatus stand as illustrated in Figs. 1 and 2 with the exception noted as to the valve 36. Pressure from the pipe 37, resisted by the valve 22, fills and equalizes in the valve chamber 28, arm 29 and mouth of the cylinder 30 and acting on 5 the piston head 42 moves the same downwardly against the tension of the spring 44, thus moving the piston rod 40 downwardly and permitting the valve 33 to seat and cut off temporarily admission of pressure from 10 the pipe 37. The downward movement of the rod 40 effects a movement of the lever 48 through an arc which performs two operations: namely, oscillation of the bell-crank lever 58 through the rod 63 and consequent one-step movement of the feeding disk 14 to the end of advancing one loaded pocket 57 into register with the hole 13 and elbow 55; and the other operation of opening 20 the entrance to the standard 19 by movement of the elbow 26 through an arc to raise the ball valve 22, such movement being effected by engagement of the lever 48 with the nut 53 and consequent downward movement of the pitman 46. It will be noted that 25 30 the range of movement provided for the lever 48 between the nuts 52, 53 permits feeding movement of the disk 14 prior to the opening movement of the valve 22. When the two operations resulting from the 35 downward movement of the piston rod 40 have been completed, the pressure trapped in the valve chamber 28 and arm 29 is exerted through the standard 19 and hole 13 to drive the charge of plastic material contained 40 in the registering pocket 57 through the elbow 55 and discharge pipe 56 to the end of depositing said charge with force as a separate entity on a surface to be coated. By this means the pressure in the blast 45 chamber is permitted to equalize with external air pressure and the way is prepared for reaction of the piston head 42 under pressure of the spring 44 to its normal position, which has the effect of returning the piston 50 rod 40 upwardly. The upward movement of the piston rod 40 has three functions: namely, returning the bell-crank 58, in preparation for the next step movement of the feeding disk, permitting the valve 22 to 55 close, and opening the valve 33 for recharging of the blast chamber 28 from the source of pressure supply. Then the operation of the movable parts of the apparatus is repeated to the conclusion of the work in 60 hand, the exhaustion of the supply of plaster, or manual closing of the valve 36; all of said movements being automatic except the operation of the latter valve. It sometimes occurs that the parts become locked by 65 complete reaction and the valves 22 and 33

become simultaneously closed or the spring 44 remains compressed, in which event the valve 31 is manually opened to release air pressure in the chamber 28.

Either or both of the nuts 52, 53 may be 70 adjusted relative to the threaded rod 46 or to each other, to regulate the relative differences in time of actuations of the said rod 46 and the bell-crank lever 58.

By the synchronizing of the feeding disk 75 operating means with the means for alternately operating the valves 22, 33 the operation of the machine is rendered automatic and little attention is required on the part of the operator. 80

I claim as my invention—

1. In a machine of the class described, a member mounted for rotary travel, a member mounted for reciprocation, a lever pivoted on said reciprocating member, a bell-crank lever suitably fulcrumed, a pawl pivoted on said bell-crank lever and adapted for engagement with said rotary member to cause step by step rotary movement thereof, a link pivotally connecting said lever and bell-crank lever, a rod extending across said lever, a member adapted to be oscillated by said rod, and means on said rod adapted for engagement by said lever to move said rod, such engaging means being so arranged that 90 movement of said rod occurs subsequent to oscillation of said bell-crank lever through said link. 95

2. An air motor, comprising a cylinder, 100 an air passage communicating with one end portion thereof and formed with a valve seat, a valve adapted to rest on said seat and close said passage, a piston mounted for reciprocation in said cylinder, valve-opening means connected with said piston and acting to hold said valve in open position at times, means acting on said piston to hold it normally in such position that the valve is in open position, said passage also being formed with a second valve seat, a valve normally resting on said seat and closing said passage, a lever pivoted to said piston, connections extending from said lever and adapted to open the second mentioned valve when the piston is moved to permit closing 110 of the first mentioned valve, and means connected with said lever for operating a work object. 115

3. An air motor, comprising a vertically arranged cylinder, an air passage communicating with the upper end of said cylinder and formed with a valve seat arranged on the axis of said cylinder, a valve adapted to rest on said seat and close said passage, said passage also being formed with a second valve seat, a valve normally resting on said seat and closing said passage, a piston-rod mounted for reciprocation in said cylinder, a piston-head on said rod intermediate of its ends, the upper end of said piston-rod be- 120 125 130

ing adapted to raise the first named valve at times, said piston-head being adapted to be depressed by air under pressure in said passage, a spring adapted to return said piston-head to its uppermost position, a lever pivoted to said piston-rod, connections extending from said lever and adapted to open

the second mentioned valve when said piston-head is depressed, and means connected with said lever for operating a work object. 10

Signed at Fairmont, in the county of Garfield and State of Oklahoma, this 20th day of December, 1918.

GILBERT E. WHITE.
